UNITED STATES PATENT OFFICE.

WILLIAM J. WARDELL, OF BROOKLYN, NEW YORK, ASSIGNOR TO AMERICAN CAN COMPANY, OF NEW YORK, N. Y., A CORPORATION OF NEW JERSEY.

SQUIRT-CAN.

1,279,487.

Specification of Letters Patent. Patented Sept. 17, 1918.

Application filed August 16, 1915. Serial No. 45,687.

PRINTED IN U.S.A. COPY

To all whom it may concern:

Be it known that I, WILLIAM J. WARDELL, a citizen of the United States, residing in Brooklyn, in the county of Kings and State 5 of New York, have invented a new and useful Improvement in Squirt-Cans, of which the following is a specification.

This invention relates in general to containers for liquids of various sorts and has 10 more particular reference to containers provided with a flexible bottom adapted to be pressed inwardly to produce ejection of the contents.

A principal object of this invention is the 15 provision of such a structure which may be closed with an ordinary screw cap.

A further object of the invention is the provision of such a structure in which the part provided with the perforation through 20 which the liquid is ejected may be readily inserted after filling.

Prior to my invention it has been generally the custom in containers or cans of this character, to provide a spout through which 25 the liquid is ejected under pressure from the bottom, which spout may or may not be closed with a screw cap. Spouts of this character are more or less relatively expensive to manufacture and they extend out 30 from the can either above it or to the side where they are readily damaged. This invention aims to eliminate these evils through the provision of a construction occupying no more room and costing little more to make 35 than the ordinary screw cap can.

Numerous other and improved objects and 40 advantages of the invention will be apparent as it is better understood from the following description when considered in connection with the accompanying drawing illustrating a preferred embodiment thereof.

On the drawing,

Figure 1 is a side elevation showing in 45 partial section a can embodying my invention;

Fig. 2 is a section through the friction plug;

Fig. 3 is a section through the top of the container with the cap and plug removed;

50 Fig. 4 is a top plan view of the plug; and

Fig. 5 is a partial view of the structure shown in Fig. 1 upon an enlarged scale.

The can shown on the drawing and embodying my invention consists of a side wall 55 11, a bottom wall 12 and an upwardly ex-

tending threaded neck 13 of usual general form and carrying a perforated plug 14 and screw cap 15. The can shown on the drawing is of circular cross section, although manifestly it may have any preferred shape. 60

Referring more particularly to Fig. 3 it will be noted that the upper end of the neck 13 extends inwardly at 16 to provide an annular horizontal flange, and downwardly at 17 to provide a friction seat wall. The 65 friction plug or cap consists in the present instance of a single sheet of metal formed into a central dome 18, an upwardly extending friction wall 19 and an outwardly extending horizontal flange 21. The center 70 of the dome is perforated at 22 to give an opening sufficiently restricted to prevent liquid within the container from flowing out unless atmospheric pressure be removed or unless added pressure be applied to the 75 liquid within the container. The plug 14 seats within the open end of the neck 13, as best shown in Fig. 5, with the friction walls 17 and 19 in tight frictional engagement and with the horizontal flanges 21 and 16 resting 80 one upon the other. The curvature of the dome central part of the plug is only sufficient to carry its highest point slightly above the top of the flange 21, this point at which the perforation 22 is located being 85 thereby a little above the plane of the neck opening, and the gasket (hereinafter mentioned) is held out of contact with and does not adhere to the container neck.

The screw cap 15 is of ordinary form and 90 consists of a top or central portion 23 and a downwardly extending flange 24, a suitable gasket packing 25 being provided over the perforation 22 to seal the container when the screw cap is turned down about the neck. 95 Around the perforation 22 is formed an upwardly extended spout portion adapted to be embedded in the gasket 25 (Fig. 5) to make a hermetic seal, and also adapted to deliver the contents of the container clear of 100 the top surface of the plug 14 so as not to collect on the same. Pressure of the screw cap aids in tightening the friction plug in place. Liquid is ejected through pressing inwardly the flexible bottom 12 in the manner ordinarily employed in squirt cans.

It is thought that the invention and many of its attendant advantages will be understood from the foregoing description, and it will be apparent that various changes may 110

be made in the form, construction and arrangement of the parts without departing from the spirit and scope of the invention or sacrificing any of its material advantages, 5 the form hereinbefore described being merely a preferred embodiment thereof.

I claim:

1. The combination of a container having a vertical inwardly presented friction seat wall; an inner cap having a vertical outwardly presented friction seat wall adapted to engage within said inwardly presented friction wall to form a tight closure, said inner cap being formed with a perforation 15 and with an upwardly extended spout portion around the perforation; an outer cap inclosing said inner cap and adjustably connected with the container; and a packing in said outer cap adapted to receive said spout 20 portion and seal said perforation.

2. The combination of a container having a screw threaded neck the top edge of which is bent inward away from the screw threaded portion and thence downward to form an 25 inwardly presented vertical friction seat wall; an inner upwardly extending cap formed with a perforation and with an outwardly presented vertical friction seat wall bent up from the lower edge of the cap and 30 adapted to engage within the friction wall of the neck to form a tight closure, and formed with a flange bent outward from the outwardly presented seat wall and adapted to engage on top of the neck to hold the 35 said nozzle and perforation at a distance above the top of the neck of the can; a screw cap engaging the said neck and in-

closing said inner cap; and a packing in the screw cap adapted to be pressed by the same over and on to said perforation to seal 40 the same.

3. In a squirt can, in combination: a container having a resilient bottom and a screw threaded neck the top edge of which is bent inward away from the screw threaded portion and thence downward to form an inwardly presented vertical friction seat wall; a domed cap formed with a perforation and an upwardly extending nozzle surrounding said perforation, and formed with an 45 outwardly presented vertical friction seat wall bent up from the lower edge of the dome and adapted to engage within the friction wall of the neck to form a tight closure, and formed with a flange bent outward from the outwardly presented seat wall and adapted to engage on top of the neck to hold the said nozzle and perforation at a distance above the top of the neck of the can; a screw cap engaging the said neck 50 and inclosing said domed cap; and a packing in the screw cap adapted to be pressed by the same over and around said nozzle and perforation to seal the same, said packing being held out of contact with the joint 55 between the inner cap and the can neck.

In testimony whereof, I have hereunto set my hand in the presence of two subscribing witnesses.

WILLIAM J. WARDELL.
